(57) **CLAIM**

The ornamental design for a dog scratch pad, as shown and described.

DESCRIPTION

FIG. 1 is a perspective view of another state of a dog scratch pad showing my new design;

FIG. 2 is a perspective view of another state of the dog scratch pad thereof;

FIG. 3 is a perspective view of the dog scratch pad thereof;

FIG. 4 is a perspective view of the dog scratch pad thereof;

FIG. 5 is a front view thereof;

FIG. 6 is a back view thereof;

FIG. 7 is a left side view thereof;

FIG. 8 is a right side view thereof;

FIG. 9 is a top view thereof; and,

FIG. 10 is a bottom view thereof.

The broken lines shown in the drawings depict portions of the dog scratch pad that form no part of the claimed design.

1 Claim, 10 Drawing Sheets
